MEANS FOR USE IN SPINNING AND IN
LIQUID-TREATING TUBULAR RAYON
PACKAGESCharles A. Huttinger, Lakewood, Ohio, assignor
to Acme Rayon Corporation, Cleveland, Ohio,
a corporation of OhioOriginal application May 5, 1934, Serial No.
724,114. Divided and this application April 7,
1936, Serial No. 73,145

4 Claims. (Cl. 242—118)

The subject matter of this application is divided out of my application Serial No. 724,114, Means for use in spinning and in liquid-treating tubular rayon packages (Patent No. 2,065,526).

5 In an application, Serial No. 724,113, Patent No. 2,089,962, I have shown, described, and claimed improved apparatus for treating fine filamentous thread; as also, described and claimed improved processes for treating such thread. A part of the 10 apparatus set forth in said application, Serial No. 724,113, is improved supports for use in liquid-treating such thread in tubular package form, and improved support-attachments for the wound-bobbin-supporting-and-rotating spindles 15 of package-spinning machines. Certain forms of package-supports and attachments shown and described in said application, Serial No. 724,113, are some of those shown, described, and claimed in the instant application.

20 The invention claimed in said application, Serial No. 724,113, relates to improved methods and apparatus for liquid-treating rayon in package form, such as cakes, wound spools or bobbins, etc., after the rayon thread has been collected in 25 such form by spinning machines from the precipitating bath in which the rayon filaments are set up. The rayon thread as so collected is comprised of a comparatively large number of filaments which are twisted as some forms of packages are being collected, and are collected 30 untwisted in other forms of packages.

The treatments to which the rayon package is subjected by the improved process and apparatus claimed in said application, Serial No. 724,113, 35 are the different treatments to which the rayon is necessarily subjected, before the precipitated and package-collected thread can be considered a final product ready for the market, such as various water washings, desulphurizing, bleaching, oiling, 40 sizing, dyeing, drying, and other purifying and finishing operations.

Primarily, the process of said application, Serial No. 724,113, consists in loosening up the package, when purifying the same in its initial collected form, so as to provide for all parts of the package their respective natural scopes of free play, relative to other parts of the package, thus effecting a natural alteration of the relative positions of all parts of the thread comprising the 45 package and of the different portions of the package. This is done without injuriously disarranging the thread or the filaments thereof, so that the package may be dried in the treated package form, preliminary to the sale thereof for the market, or to the rewinding thereof into some other

5 form of package for such sale, without inducing strains or an immobile condition in any portion of the package which would result in a non-uniform dyeing or barred effect. The purification and other treatments of the package are carried out without unduly impairing the tenacity and elasticity of the thread required for later handling and processing or for use, and without setting up local tension areas or non-uniform strains. Essentially, the process consists in pulsating the 10 package body by means of the treating liquid on the openings of improved forms of skeleton inserts and bobbins upon which the package is mounted and while spaced portions of the latter are free 15 to move to a predetermined extent, through said insert openings, under the pressure of the treating liquid.

Some of the forms of the bobbins, above-mentioned, upon and through the openings of which the pulsating package body is free to move, and 20 some of the forms of the improved bobbin-attachments, form the subject matter claimed in the instant application.

In said application, Serial No. 724,113, there is 25 a disclosure of processes of, and means for, causing the treating liquid alternately to flow in opposite directions through tubular rayon packages, viz., from the outer face to the inner face, and from the inner face to the outer face. When the treating liquid passes from without the tubular 30 rayon package through the body thereof and into the interior of the package, the package is deformed by reason of parts thereof moving inwardly through the openings of the insert or bobbin upon which the package is mounted. This 35 inward movement is under the pressure of the treating liquid and is preferably permitted up to a predetermined maximum extent, and loosens up the package to a degree and permits a natural 40 altering of the relative positions of the parts of the thread comprising the package and of different portions of the package.

Said other application, Serial No. 724,113, also 45 explains how rayon packages of the character therein shown are spun so that the strands of the outer face of the package prevent any material enlargement of the package perimeter. Therefore, the pressure of the treating liquid from within the package outwardly, i. e., when the 50 flow of treating liquid is toward the outer face of the package, does not bulge or deform the package outwardly so as to increase its perimeter, under any pressures that are practically usable for such treatments. However, those portions of the package which are not moved inwardly by 55

liquid passed inwardly of the package body are adjusted somewhat outwardly during such treatment, as clearly shown in the accompanying drawing and as will hereinafter be fully described. Explanation is also made of the fact that at some stages of the process complete passage of the treating liquid through the package would not be effected, but only a tendency to pass through the package in the direction of liquid flow; also, that after the package had once been inwardly deformed, it would reestablish itself in its original form, or tend to so reestablish itself, when the direction of liquid flow is again outwardly of the package.

15 Said other application, Serial No. 724,113, makes a disclosure of certain methods and means for assembling a plurality of packages in a series of vertically-aligned tiers in a treatment casing within which the packages are subjected to the 20 action of the treating liquid. Means are disclosed for recirculating the treating liquid through the treatment casing and the packages mounted therein, and for automatically and adjustably periodically reversing the direction of liquid flow.

25 Said other application, Serial No. 724,113, illustrates the use and application of the improved process and apparatus therein disclosed, by reference to a water-washing of rayon cakes and wound rayon bobbins. It is also disclosed in said 30 other application that packages of the wound bobbin or spool shape are collected from the spinning machines upon perforated bobbins or supports and that it is the purpose of the invention disclosed in said application to liquid-treat the 35 wound bobbins in situ upon the same perforated bobbins. However, inasmuch as the liquid treatment pulsates the packages upon openings in the bobbins, which openings would render difficult, if not impossible, the spinning of the wound bobbin 40 in perfect cylindrical formation, removable bobbin attachments are provided for covering these openings during the spinning operation.

Some forms of the removable bobbin attachments above-mentioned form part of the subject 45 matter claimed in the instant application, being termed "means for use in spinning annular rayon packages and for liquid-treating the collected packages in situ". The claims of the instant application are directed to means for use in spinning and in liquid-treating annular rayon packages, wherein no limitations are included relating to stop members for limiting the movements of spaced portions of the package through the 50 openings of the skeleton bobbins; whereas, the claims of the parent application, Serial No. 724,114, from which the subject matter of the instant application has been divided out, are directed to forms of skeleton inserts and bobbins having such stop means.

60 The annexed drawing and the following description set forth in detail certain means illustrating my improved rayon-package supports and improved support-attachments, such means disclosing, however, only a few of the various forms in which the principle of the improved supports and attachments may be embodied.

In said annexed drawing:

Figure 1 is a fragmentary vertical section of a fragmentary portion of a treatment casing in which a plurality of rayon packages of the wound bobbin or spool type are mounted for liquid treatment, the packages being mounted upon special skeleton bobbin supports.

Figure 2 is a plan section, taken on the plane indicated by the line 2—2, Figures 1 and 3, the

shape in which the wound bobbin is spun, or, if it has been deformed inwardly by previous liquid treatment, in which it tends to reestablish itself, when the flow of treating liquid is from within outwardly, being shown in full lines, and the shape assumed by the wound bobbin package, or which it tends to assume, when the flow of treating liquid is from without inwardly, being suggested by dot-and-dash lines;

Figure 3 is a vertical axial section, taken in the plane indicated by the line 3—3, Figure 2;

Figure 4 is a fragmentary axial section, taken in the plane indicated by the line 4—4, Figure 2;

Figure 5 is a fragmentary axial section of the wound-bobbin-supporting-and-rotating portion of a spindle of a spinning machine provided with a perforated bobbin support and a support attachment, both of which embody my improvements, the attachment serving to hold the thread circular as it is being collected from the precipitating bath and thus insure cylindrical inner and outer surfaces for the wound collected bobbin. Thus, a regularly annular wound bobbin package is gathered even if the wound bobbin being gathered is supported only at spaced points by the support or, in other words, is being gathered on a perforated support having comparatively large windows or openings; and

Figure 6 is a cross-section, taken in the plane indicated by the line 6—6, Figure 5.

Referring to the annexed drawing in which the same parts are indicated by the same respective numbers in the several views, and particularly referring to Figure 1, I therein disclose a fragmentary portion of a movable treatment casing 3 having an interior rubber covering 49 and an exterior rubber covering 50 forming part of the protective means of the treatment casing 3 within which the wound rayon packages are mounted for liquid treatment.

Referring particularly to Figures 1, 2, 3 and 4, there is therein shown a form of support 10' for rayon packages of the wound spool or bobbin type. A fragmentary portion of a vertical tier of such wound bobbin packages 7 is shown in Figure 1 mounted for liquid treatment, the vertically adjacent wound bobbins 7 being spaced apart by upper and lower laterally-extended flanges 141 of annular spacers 140. The respective wound bobbins 7 are spaced apart a distance equal to the combined depth of the flange portions of a spacer 140, and the body portions of the spacers 140 are spaced apart by the bobbin supports 10'. These supports 10' each comprise a pair of end rings 142 connected by a plurality of spaced longitudinal bars 143 having split rubber sheaths 144. As is well-known in the art, and as is clearly shown in Figure 1, the wound bobbin type of package is gathered or spun with tapered end faces, so I make the flanges 141 of the spacers 140 also of tapered formation to conform to the end faces 7' of the wound bobbin 7, and thus cause the end faces 7' of the wound bobbin 7 and the adjacent faces of the flanges 141 closely to contact one with the other throughout the entire distance wherein they are in vertical alignment. When the wound rayon bobbin 7 is mounted upon the support 10' and is subjected to the action of a treating liquid applied to the outer surface of the wound bobbin 7, spaced wound bobbin portions pass through the openings of the bobbin 10' between the respectively adjacent bars 143 and assume the positions clearly indicated by dot-and-dash lines in Figure 2, or tend to assume these positions, the inner face and the outer face

of the wound bobbin 7, under these conditions, being indicated by the respective numbers "145" and "146", both being of irregular or wavy outline.

Referring particularly to Figures 5 and 6, a type of bobbin such as shown in Figure 1 is provided, but these Figures 5 and 6 also disclose a bobbin attachment applied to the wound-bobbin-collecting spindle of a spinning machine, whereby the wound bobbin can be collected with substantially cylindrical inner and outer faces although it is being collected on a bobbin or support which is provided with windows or openings large enough to permit the inward and outward pulsation of the wound bobbin package through such openings when the package is being processed by a treating liquid applied thereto alternately in opposite directions. In other words, the wound bobbin package 7 is gathered upon the same support or bobbin as is used for the liquid-treating operations applied to the wound bobbin subsequent to the collecting or spinning of the wound bobbin, even though this support is provided with the comparatively large openings or windows.

The bobbin attachment above-mentioned is formed with a hub member 147 secured to the bobbin-rotating spindle 148 of a spinning machine by means of a set screw 149. Formed upon the outer surface of the hub member 147 are a plurality of transversely spaced ears 151 to which are pivotally secured by means of pins 152 a plurality of spaced longitudinal arms 153 having hub portions 154 mounted on the pins 152, which hub portions 154 are formed with heels 154' closely contacting the outer surface of the hub member 147. Each of the arms 153 is formed with a plate 155 having an arcuate exterior surface of a width slightly less than the arc between the exterior collecting surfaces of contiguous bobbin bars 143, each plate 155 lying between two adjacent bars and having its outer surface lying in the circle defined by the exterior collecting surfaces of the bobbin bars 143. These plates 155 have end extensions 156 adapted to contact at their outer side surfaces with the inner surface of one of the bobbin end rings 142. When the wound bobbin package 7 is being gathered or collected by the spinning machine, the plates 155 form wound-bobbin-supporting members between the respectively adjacent bars 143 of the bobbin 10' and their exterior collecting surfaces form with the exterior collecting surfaces of the bars 143 a substantially continuous cylindrical collecting surface so that the bobbin package can be effectively and properly collected and wound. All parts of the bobbin attachment capable of contaminating the wound bobbin package are made of hard rubber, or Bakelite, or other non-corrosive material, or may be covered with non-corrosive material.

Extended inwardly from the center of the wound-bobbin-supporting plates 155 are radial webs 157 having inner end clamping pad portions 158 of arcuate formation. These pad portions 158 are adapted to contact the outer cylindrical surface of a spreading head 160 having an extended conical portion 160' and formed upon a rod 159 having a handle 162 at one end and a pin extension 161 at the other end adapted to engage a recess 150 in the hub member 147. Outward movement of the rod 159 is limited by an enlarged shoulder portion 174 thereof which is adapted to contact the inner ends of the pads 158. When there is no bobbin on the spinning machine, and therefore the attachment is not sup-

ported, the arms 153 are collapsed by a rubber band 173 seated in a groove formed in the exterior face of the plates 155, which band 173 prevents the lowermost arms 153 from falling outwardly. The arms 153 are prevented from falling inwardly by reason of the contact of the heel members 154' with the outer surface of the hub member 147.

When it is desired to spin a rayon bobbin 7 upon a bobbin or support 10' and upon the spindle 10 of a spinning machine having my improved attachment, the bobbin 10' is applied to the attachment, which is fixed to the spinning machine spindle, in the following manner. The bobbin 10' is passed over the arms 153 of the attachment 15 with the bars 143 of the bobbin passing between the adjacent edges of adjacent wound-bobbin-supporting plates 155, as shown in Figure 6, and the end extensions 156 of the plates 155 passing through one end ring 142 of the bobbin 10', as 20 shown in Figure 5. Meanwhile, the inner extension 161 of the rod 159 has been positioned in its innermost position in the recess 150 of the hub member 147. This rod 159 is then pulled outwardly by means of the handle member 162, the 25 conical head portion 160' facilitating the entrance of the head 160 within the circle defined by the clamping plates 158, the outward movement of the rod 159 being continued until the shoulder 174 engages the inner ends of the clamp- 30 plates 158, as clearly shown in Figure 5. Thus the pads 158 are tightened so as to position the wound-bobbin-supporting plates 155 substantially in the circle defined by the rubber sheaths 144 of the bobbin bars 143, which is the circle that it 35 is desired to define by the inner face of the wound bobbin 7 when it is gathered or spun.

Important advantages attach to the spinning of the rayon packages of bobbin formation upon bobbins which are of such constructions that they 40 can also be used as supports, after spinning, for the necessary purification and other processing. It is necessary with previous types of bobbins to unwind the rayon package from the bobbin and rewind into other package forms, after washing, 45 and before subsequent processing, and in so doing, the rayon fibres are damaged, and other injurious results occasioned. If the rayon package upon the previous types of bobbin is not so rewound, the benefits of the inward shrinkage of 50 the package obtained by the improved process of my application Serial No. 724,113, cannot be realized. My improved attachments for the wound-bobbin-supporting shafts of spinning machines 55 permit proper collection of the rayon bobbins upon perforated bobbins which then serve as suitable supports upon which the wound rayon bobbins remain mounted for subsequent processing. As will be clearly seen in Figure 6, the plates 155 do not fill the entire collecting surface portions 60 between the adjacent bars 143, but do complete the collecting surface to an extent sufficient to make a continuous collecting surface from a practicable standpoint. In other words, the comparatively slight spaces between the edges of the 65 plates 155 and the adjacent bars 143 are not large enough to prevent the collection of the wound bobbin with substantially cylindrical inner and outer faces.

My improved forms of bobbins are also adaptable to the well-known drip-washing of rayon packages. The wound bobbins mounted on the bobbins may or may not be rotated while water is permitted to drip over the wound bobbins. Preferably, the bobbins are supported between spacers 75

held in position similar to the stacking arrangement of the wound bobbins and bobbins, shown in Figure 1. Furthermore, in lieu of the drip method, the treating liquid can be applied to the 5 rayon packages mounted on my improved bobbins and stacked as shown in Figure 1, through a perforated tubular pipe located within the stack, the liquid being applied without pressure, thus loosening up the package and inducing inner movement thereof.

When spinning wound bobbin packages, the thread is gathered untwisted, and therefore it is necessary subsequently to twist the thread on a separate machine known as a "twister" or a 10 "spinner". I wish to point out that the elongated windows of my improved forms of bobbin do not offer resistance to free twisting, since the bobbin with the wound rayon bobbin mounted on it is revolved at a high speed during the twisting 15 operation causing the cross-sectional shape of the wound bobbin package to take a form similar to that which it assumes, or tends to assume, when it is subjected by my improved process to the action of a treating liquid moving from within 20 the package outwardly. Since the rayon thread is dry when being twisted, no unequal strains such as my improved bobbin supports seek to eliminate 25 are set up by the centrifugal action.

What I claim is:

- 30 1. Means for use in spinning annular rayon packages and for liquid-treating the collected packages in situ comprising a skeleton bobbin having spaced package-supporting elements formed each with a collecting surface, said surfaces being all equally spaced from a common point and defining a cylindrical collecting surface, bobbin-rotating means upon which the bobbin is removably mounted, said rotating means including spaced elements between the adjacent 35 pairs of which the bobbin elements are positioned, the spaced elements of the bobbin-rotating means having collecting surfaces disposed in the plane of said cylindrical collecting surface and rendering said cylindrical collecting surface substantially continuous, and means for holding the elements of the bobbin-rotating means releasably in position, whereby when the bobbin and the wound package collected thereon are removed from the bobbin-rotating means the bobbin forms a close-fitting support for the wound package and holds the latter against longitudinal displacement.
- 40 2. Means for use in spinning annular rayon packages and for liquid-treating the collected packages in situ comprising a skeleton bobbin having spaced package-supporting elements formed each with a collecting surface, said surfaces being all equally spaced from a common point and defining a cylindrical collecting surface, bobbin-rotating means upon which the bobbin is removably mounted, said rotating means includ-

ing spaced plates between the adjacent pairs of which the bobbin elements are positioned, said spaced plates having arcuate collecting surfaces disposed in the plane of said cylindrical collecting surface and rendering said cylindrical collecting surface substantially continuous, and means for holding said plates releasably in position, whereby when the bobbin and the wound package collected thereon are removed from the bobbin-rotating means the bobbin forms a close-fitting support for the wound package and holds the latter against longitudinal displacement.

3. Means for use in spinning annular rayon packages and for liquid-treating the collected packages in situ comprising a skeleton bobbin having spaced package-supporting elements formed each with a collecting surface, said surfaces being all equally spaced from a common point and defining a cylindrical collecting surface, bobbin-rotating means upon which the bobbin is removably mounted, said rotating means including spaced plates between the adjacent pairs of which the bobbin elements are positioned, said spaced plates alternating with the bobbin elements and having arcuate collecting surfaces disposed in the plane of said cylindrical collecting surface and rendering said cylindrical collecting surface substantially continuous, means for actuating said plates into, and holding them in, collecting position, and means for collapsing said plates inwardly, whereby when the bobbin and the wound package collected thereon are removed from the bobbin-rotating means the bobbin forms a close-fitting support for the wound package and holds the latter against longitudinal displacement.

4. Means for use in spinning annular rayon packages and for liquid-treating the collected packages in situ comprising a bobbin having end rings and spaced rigid bars connecting said rings, said bars each being formed with an exterior collecting surface, said surfaces being all equally spaced from a common point and defining a cylindrical collecting surface, bobbin-rotating means upon which the bobbin is removably mounted, said rotating means including spaced plates between the adjacent pairs of which said bars are positioned, said spaced plates having arcuate collecting surfaces disposed in the plane of said cylindrical collecting surface and rendering said cylindrical collecting surface substantially continuous, and means for holding said plates releasably in position, whereby when the bobbin and the wound package collected thereon are removed from the bobbin-rotating means the bobbin forms a close-fitting support for the wound package and holds the latter against longitudinal displacement.

CHARLES A. HUTTINGER.
